UNITED STATES PATENT OFFICE.

HORACE A. LOCKWOOD, OF KANSAS CITY, MISSOURI.

PLEASURE-RAILWAY.

No. 877,100

Specification of Letters Patent.

Patented Jan. 21, 1908.

Application filed January 24, 1907. Serial No. 353,798.

To all whom it may concern:

Be it known that I, HORACE A. LOCKWOOD, a citizen of the United States, residing at Kansas City, in the county of Jackson 5 and State of Missouri, have invented certain new and useful Improvements in Pleasure-Railways, of which the following is a specification.

My invention relates to improvements in 10 pleasure railways.

The object of my invention is to provide a pleasure railway in which the cars may be rapidly and safely propelled around an endless track disposed so that the cars move at 15 times at constantly accelerated speed and to different altitudes, finally returning by gravity to the starting point.

The novel features of my invention are 20 hereinafter fully described and claimed.

In the accompanying drawings illustrative 25 of my invention, Figure 1 is a plan view of the track and car propelling mechanism. Fig. 2 is a vertical sectional view taken on the dotted line *a*—*b* of Fig. 1. Fig. 3 is a 30 vertical sectional view taken on the dotted line *c*—*d* of Fig. 1. Fig. 4 is a cross section of a portion of the track taken on the dotted line *e*—*f* of Fig. 5, and showing the rear end 35 of a car mounted on the track. Fig. 5 is a side elevation view of one of the cars adapted to be employed with my invention, the view showing a portion of the track and its support, a portion of the track support being shown in vertical section. Fig. 6 is a side 40 elevation view of the car propelling member 35 in engagement with the member 32 of the car. Fig. 7 is a horizontal sectional view taken on the dotted line *g*—*h* of Fig. 2. Fig. 45 8 is a vertical sectional view taken on the dotted line *i*—*j* of Fig. 1, showing one form of track brake employed. Fig. 9 is a vertical sectional view taken on the dotted line *k*—*l* of Fig. 1, showing another form of track 50 brake employed. Fig. 10 is a cross section on the line *m*—*n* of Fig. 6.

Similar characters of references denote similar parts.

The endless track comprises two spiral 55 portions each of which encircles a vertical axis, the spirals being preferably volute spirals 1 and 2, preferably disposed with the inner coils gradually rising to the outer and upper convolutions or coils. The ends of the spirals are connected by means of the track

portions 3 and 4, the portion 4 connecting 55 the upper end of one spiral with the upper end of the other spiral, and the portion 3 connecting the lower end of one spiral with the lower end of the other spiral. The convolutions of the volute spirals 1 and 2 preferably 60 run in opposite directions, and the connecting portions of the track denoted by 3 and 4, therefore, cross each other. The spirals 1 and 2 are mounted preferably upon the upper sides of two saucer shaped supports 5 65 and 6 provided each adjacent its center with an opening 7 through which the track extends at the lower end of the adjacent spiral portion. The saucer shaped supports 5 and 6 are formed of any suitable material, and 70 are in turn supported by means of vertical posts 8 the lower ends of which are supported by any suitable means. The opening 7 of the support 5 is not directly in the center, but is adjacent to the center, the central portion of the support 5 being employed as a landing place for the passengers, said central portion being provided with an opening 9 through which the passengers may ascend or descend by means of stairs 10.

The rails 11 of the track are preferably 80 mounted on a horizontal support 12 which in turn is mounted on longitudinal stringers 13 mounted on the upper sides of the saucer shaped supports 5 and 6. A car or cars 14 85 are mounted on the track, each car having secured to its under side between the forward and rear wheels 15 an inverted U shaped bar, the vertical arms of which project downward below and at opposite side edges of the support 12. On the inner sides of the vertical arms of the U bar 16 are rotatively mounted friction rollers 17 disposed below the support 12 and normally out of contact therewith. These rollers 17 prevent the car from 90 leaving the track.

A vertical shaft 18 extends axially through the bottom of the support 5, which support serves for the upper bearing of said shaft, the lower end of the shaft being rotatively 100 mounted in a vertical hole provided in the horizontal plate 19 which is mounted on the ground. The shaft 18 is rotated by any suitable means. For this purpose I have illustrated a motor, such as an electric motor 105 20 having a driving shaft 21 on which is secured a pulley 22 which is connected by a belt 23 with a pulley 24 secured on a hori-

zontal rotary shaft 25 mounted in bearings 26 and having secured to it a screw 27 the threads of which mesh with the peripheral teeth of a worm gear wheel 28, said gear wheel being secured on the driving shaft 18. The motor 20 is driven so as to rotate the shaft 18 contrary to a clockwise direction, as viewed in Fig. 1. A car engaging and propelling means is carried by the shaft 18. The preferable mechanism for this purpose comprises a vertical member 29 rigidly secured to the shaft 18 above the track. Said member 29 is provided with a curved arm 30 of channel form, the groove, denoted by 31 being in the lower side of the arm 30. The grooved arm 30 is curved so as to have its under side parallel with the upper side of the saucer shaped support 5. On the rear end of each car 14 is secured a vertical plate 32, which is curved at its upper end and side edges. The plate 32 is adapted to enter the groove 31 of the arm 30, and the car thereby be propelled by said arm when the shaft 18 is rotated in the proper direction.

As shown in Fig. 6, the arm 30 at opposite ends has recesses 33 provided in the forward side of the channel. These recesses 33 permit the plate 32 to enter and leave the groove 31 of the arm 30 while the shaft 18 is rotating.

In Fig. 8 is shown a brake provided between the rails of the spiral 1 by which the car may be stopped automatically soon after it enters the said spiral. This brake comprises an inclined plank 34, the lower end of which is pivoted between the stringers 13, the plank extending from its pivotal point upwardly through a longitudinal slot 35 in the support 12. The upper end of the plank 34 is between the rails of the track and extends upwardly sufficiently to strike the under side of the car 14. A coil spring 36 has its lower end supported on the support 5, the upper end bearing upon the under side of the plank 34 with sufficient pressure to stop the car when the car strikes and bears down the upper end of the plank 34.

In Fig. 9 is illustrated a brake similar to the one just described, the plank 34' in this brake being convex on its upper side. Any suitable number of brakes corresponding to the one shown in Fig. 9 may be inserted at convenient places between the rails for the purpose of slackening the speed of the cars as they pass by gravity down the spiral portion 2 of the track. The curvature on the upper side of the plank 34' is for the purpose of offering resistance to the passage of the cars without stopping them, the strength of the springs 36 supporting the planks 34" being only sufficient to retard but not stop the cars.

In operating my invention, the car while being held by the brake plank 34 at the lower part of spiral portion 1 is loaded with passen-

gers. The motor 20 is then started, thus causing the shaft 18 to revolve with the member 29 having the arm 30. The disposition of the recess 33 at the inner end of the inclined arm 30 is such that as the arm 30 is revolved, the member or plate 32 of a car located at the starting place adjacent the brake plank 34, will enter the recess 33 adjacent the shaft 18. As the shaft 18 continues to rotate the car will be propelled by means of the channel arm 30 so as to travel upward from the lower part of the spiral 1 to the upper end thereof. As the car passes around the convolutions of the spiral 1, the plate or member 32 will travel lengthwise of the groove 31, so that by the time that the car reaches the upper and outer convolution of the spiral 1, the plate or member 32 will be opposite the recess at the outer end of the arm 30, and the car will be free to pass from the spiral 1 along the connecting portion 4 of the track to the upper and outer convolution of the spiral portion 2 of the track. The car will then run in a reverse direction from the upper end of spiral 1 to the lower end thereof, and thence by the track portion 3 to the lower end of spiral portion 1, passing through the opening 7 of support 5, and along the lower inner coil of spiral 1 to the brake plank 34, at which place the car is stopped. The relative disposition of the plate 32 and inner end of the arm 30 may be such that when the car is stopped at the plank 34, the arm 30 will not engage the plate 32. The car may then be loaded or unloaded while over plank 34. After being loaded, the car is to be pushed by hand along the lower coil of spiral 1 until it reaches a position in which the arm 30 will strike the plate or member 32.

As the car passes upward along the spiral portion 1 of the track it will have its speed gradually and constantly accelerated until it passes from spiral 1 onto portion 4 of the track. As the car runs down the spiral 2, the brake planks 34' will reduce its speed. The car passing from the larger to the smaller coils in spiral 2 will, if the inclination be not too great, have its speed reduced by track friction.

Having thus described my invention, what I claim and desire to secure by Letters Patent, is:

1. In a railway, the combination with a track disposed in coils arranged in volute form, of a rotary shaft disposed axially within said coils, and means carried by said shaft for engaging and propelling a car or cars along said track.

2. In a railway, the combination with a track disposed in coils arranged in volute form, the track gradually rising from the inner to the outer coil, of a rotary shaft disposed axially within said coils, and means carried by said shaft for engaging and propelling a car or cars along said track.

3. In a railway, the combination with a track disposed in coils arranged in volute form, of rotating means for engaging and propelling a car or cars along said track.
- 5 4. In a railway, the combination with a track disposed in coils arranged in volute form, the track gradually rising from the inner to the outer coil, of rotating means for engaging and propelling a car or cars along said track.
- 10 5. In a railway, the combination with a track disposed in spiral coils around a vertical axis, of a vertical shaft disposed axially within said coils, means for rotating said shaft, and means carried by said shaft for engaging and propelling a car or cars upward along said track.
- 15 6. In a railway, the combination with a track disposed in coils arranged spirally around a vertical axis, of a rotary vertical shaft disposed axially in said coils, and a member carried by said shaft and extending transversely across said track and having means for engaging and propelling a car along said track.
- 20 7. In a railway, the combination with a track disposed in coils arranged in volute form, of a rotary vertical shaft disposed axially in said coils, and a member carried by said shaft and extending across said coils and adapted to engage and propel a car along said track.
- 25 8. In a railway, the combination with a track disposed in coils arranged in volute form, the track rising from the inner to the outer coil, of a rotary shaft disposed axially in said coils, and a member carried by the shaft and extending across said coils and adapted to engage and propel a car along said track.
- 30 9. In a railway, the combination with a track disposed in coils arranged in volute form, of a rotary shaft disposed vertically and axially in said coils, a car on said track having a vertical member secured thereto, and a member carried by the said shaft and provided with a grooved portion extending across said coils and adapted to receive therein said member attached to said car, whereby the car may be engaged and propelled by the member carried by the shaft when the shaft is revolved.
- 35 10. In a railway, the combination with a saucer shaped support having an opening adjacent the center, of a volute formed track mounted on said support, one end of the track extending through said opening, the track rising gradually from said opening to the outer coil of the volute.
- 40 11. In a railway, the combination with a saucer shaped support having an opening adjacent the center, of a volute formed track mounted on said support, the lower inner coil of the volute extending through said opening, a car mounted on said track, and means for engaging said car and propelling it upwardly along said track.
- 45 12. In a railway, the combination with a saucer shaped support, of a track mounted on said support and disposed in coils arranged in volute form, a shaft disposed axially in said coils, means for rotating said shaft, a car on said track, and means carried by said shaft for engaging and propelling the car along the track when the shaft is rotated.
- 50 13. In a railway, the combination with a saucer shaped support, of a track disposed in coils arranged in volute form upon said support, a shaft disposed axially in said coils, means for rotating said shaft, a car on said track, and a member secured to the shaft and extending across said coils and having means for engaging and propelling the car along the track when the shaft is rotated.
- 55 14. In a railway, the combination with a saucer shaped support, of a track disposed in coils arranged in volute form upon said support, a shaft disposed axially in said coils, means for rotating said shaft, a car on said track having a member secured thereto, and an arm secured to said shaft and extending across said coils and provided on its underside with a groove disposed transversely to the track and adapted to receive therein the member on the car, whereby the car may be propelled when the shaft is rotated.
- 60 15. In a railway, an endless track formed in two spirals encircling two vertical axes, the upper and lower ends of one spiral connecting respectively with the upper and lower ends of the other spiral.
- 65 16. In a railway, an endless track comprising two volute spirals encircling vertical axes, the ends of one spiral connecting with ends of the other spiral.
- 70 17. In a railway, an endless track comprising two volute spirals encircling respectively two vertical axes, the track in each spiral rising gradually from the inner to the outer coil, the upper and lower ends of one spiral connecting respectively with the upper and lower ends of the other spiral.
- 75 18. In a railway, the combination with an endless track formed in two spirals encircling vertical axes, the upper and lower ends of one spiral connecting with corresponding ends of the other spiral, of a car on said track, and means for propelling said car along the track from the lower to the upper end of one of said spirals.
- 80 19. In a railway, the combination with an endless track formed in two spirals encircling vertical axes, the upper and lower ends of one spiral connecting with corresponding ends of the other spiral, of a car on said track, an axial shaft located in one spiral, means for rotating said shaft, and means connected with said shaft for engaging and propelling said car on the adjacent spiral portion of the track when the shaft is rotated.

20. In a railway, the combination with an endless track formed in two spirals encircling vertical axes, the upper and lower ends of one spiral connecting with corresponding ends of the other spiral, of an axial rotary shaft located in one spiral, and car engaging and propelling means carried by said shaft. 65
21. In a railway, the combination with an endless track formed in two spirals encircling vertical axes, the upper and lower ends of one spiral connecting with corresponding ends of the other spiral, of a car on said track, and car engaging means rotative around the axis of one of the spirals. 10
22. In a railway, the combination with an endless track formed in two spirals encircling vertical axes, the upper and lower ends of one spiral connecting respectively with corresponding ends of the other spiral, of an axial shaft located in one spiral, means for rotating said shaft, and car engaging means carried by said shaft. 15
23. In a railway, the combination with an endless track formed in two volute spirals encircling vertical axes, the ends of one spiral connecting respectively with the ends of the other spiral, of a car on said track, and means for propelling the car along the track from the lower to the upper end of one of 25 said spirals. 25
24. In a railway, the combination with an endless track formed in two spirals encircling vertical axes, the ends of one spiral connecting respectively with the ends of the other spiral, of a rotary axial shaft located in one of said spirals, and car engaging means carried by said shaft. 35
25. In a railway, the combination with an endless track formed in two spirals encircling vertical axes, the ends of one spiral connecting respectively with the ends of the other spiral, of an axial shaft located in one spiral, means for rotating said shaft, and an arm carried by said shaft and having means for 40 engaging and propelling a car along the track when the shaft is rotated. 45
26. In a railway, the combination with an endless track formed in two volute spirals encircling vertical axes, the ends of one spiral connecting respectively with the ends of the other spiral, of car engaging and propelling means rotative around the axis of one of said spirals. 50
27. In a railway, the combination with an endless track formed in two volute spirals encircling vertical axes, the ends of one spiral connecting respectively with the ends of the other spiral, of a shaft disposed axially in one spiral, means for rotating said shaft, and a car engaging and propelling member carried by said shaft and extending transversely across the coils of one volute spiral. 55
28. In a railway, the combination with an endless track formed in two volute spirals encircling vertical axes, the ends of one spiral connecting respectively with the ends of the other spiral, of a shaft rotatively and axially mounted in one spiral, and car engaging and propelling means connected with said shaft. 60
29. In a railway, an endless track comprising two volute spirals encircling vertical axes, the convolutions of the spirals running in opposite directions around said axes, and the ends of one spiral connecting respectively with the ends of the other spiral. 75
30. In a railway, an endless track comprising two volute spirals encircling vertical axes, the convolutions of the spirals running in opposite directions, the track in said spirals rising from the inner to the outer coils, and the ends of one spiral connecting respectively with the ends of the other spiral. 80
31. In a railway, an endless track comprising two volute spirals encircling vertical axes, the convolutions of the spirals running in opposite directions, the track having crossed portions connecting respectively the ends of one spiral with the ends of the other spiral. 85
32. In a railway, an endless track comprising two volute spirals encircling vertical axes, the convolutions of the spirals running in opposite directions, the track in each spiral rising from the inner to the outer coil or convolution, the track having crossed portions connecting respectively the ends of one spiral with the ends of the other spiral. 90
33. In a railway, the combination with an endless track comprising two volute spirals encircling vertical axes, the convolutions of the spirals running in opposite directions, the track having crossed portions connecting respectively the ends of one spiral with the ends of the other spiral. 95
34. In a railway, the combination with an endless track comprising two volute spirals encircling vertical axes, the track having portions connecting the ends of one spiral with the ends of the other spiral, of a shaft rotatively and axially mounted in one spiral, and means carried by said shaft for engaging and propelling a car along the track from the lower end of one spiral to the upper end thereof. 100
35. In a railway, the combination with an endless track comprising two volute spirals encircling vertical axes, the convolutions of the spirals running in opposite directions, the track having crossed portions connecting the ends of one spiral with the ends of the other spiral, of a shaft rotatively and axially mounted in one spiral, and car engaging and propelling means connected with said shaft. 110

and extending transversely across the convolutions of the adjacent spiral.

36. In a railway, the combination with two saucer shaped supports each having an opening adjacent its central bottom portion, of an endless track comprising two volute spirals mounted respectively upon said supports, the lower ends of the spirals extending respectively through said openings in said supports, and the track having portions connecting the ends of one spiral respectively with the ends of the other spiral.

37. In a railway, the combination with two saucer shaped supports each having an opening adjacent its central bottom portion, of an endless track comprising two volute spirals mounted respectively upon said supports, the lower ends of the spirals extending respectively through said openings, the track having a portion connecting the lower ends of the spirals and a portion connecting the upper ends of the spirals.

38. In a railway, the combination with two saucer shaped supports each having an opening adjacent its central bottom portion, of an endless track comprising two volute spirals mounted respectively upon said supports, the lower ends of the spirals extending respectively through said openings, the track having portions connecting the ends of one spiral with the ends of the other spiral, and means for engaging and propelling a car along the track from the lower to the upper end of one of said spiral portions of said track.

39. In a railway, the combination with two saucer shaped supports having each an opening adjacent its central portion, of an endless track comprising two volute spiral portions mounted on said supports respectively, the lower ends of the spirals extending through said openings, the track having portions connecting the ends of one spiral portion with the ends of the other spiral portion, a shaft disposed axially in one spiral, means for rotating said shaft, and means connected with said shaft for engaging and propelling a car along the track from the lower end to the upper end of one of the spiral portions of the track.

40. In a railway, the combination with two saucer shaped supports each having an opening adjacent its center, of an endless track comprising two volute spirals mounted on said supports respectively, the lower ends of said spirals extending through said openings respectively, the track having portions connecting the ends of one spiral with the ends of the other spiral, an axial rotary shaft in one of said spirals, means for rotating said shaft, and a member secured to said shaft and extending transversely across the coils of the adjacent spiral and provided with means for engaging and propelling a car along the track from the lower end to the

upper end of the adjacent spiral when said shaft is rotated.

41. In a railway, the combination with a track having coils arranged in volute form around a vertical axis, of a shaft rotatively and axially mounted in said coils, a car on said track, means connected with said shaft for engaging and propelling the car along the track when the shaft is rotated, and means independent of said car engaging means for controlling the speed of movement of the car.

42. In a railway, the combination with an endless track comprising two volute spirals encircling vertical axes, the track having portions connecting the ends of one spiral with the ends of the other spiral, of means for engaging and propelling a car along the track from the lower to the upper end of one spiral, and means for controlling the speed of the car around the coils of the other spiral.

43. In a railway, the combination with an endless track comprising two volute spirals encircling vertical axes, the track having portions connecting the ends of one spiral with the ends of the other spiral, of car engaging and propelling means rotatable around the axis of one spiral, and speed controlling means located adjacent the track in the other spiral and provided with means for engaging a car and reducing the speed thereof.

44. In a railway, the combination with an endless track comprising two volute spirals encircling vertical axes, the track having portions connecting the ends of one spiral with the ends of the other spiral, of a shaft disposed axially in one spiral, means for rotating said shaft, a member secured to said shaft and having an arm extending transversely over the coils of the adjacent spiral, and a car on said track and provided with a member adapted to be engaged by said arm, whereby the car is propelled along the coils of the spiral adjacent to said arm when the shaft is rotated.

45. In a railway, the combination with an endless track comprising two volute spirals encircling vertical axes, the track having portions connecting the ends of one spiral with the ends of the other spiral, of a shaft disposed axially in one spiral, means for rotating said shaft, a member secured to said shaft having an arm extending across the coils of the adjacent spiral, the arm having a longitudinal groove on its under side, and a car on said track having a member adapted to enter said groove and travel lengthwise therein when the car is propelled along the track by said arm.

46. In a railway, an endless track comprising two volute spirals, the convolutions running in opposite directions, the upper and lower ends on one spiral connecting respectively with corresponding ends of the other spiral.

47. In a railway, the combination with an

endless track comprising two volute spirals, the convolutions of which run in opposite directions, and the upper and lower ends of one spiral connecting with corresponding ends of the other spiral, of a car propelling means for propelling the car along the track.

In testimony whereof I have signed my

name to this specification in presence of two subscribing witnesses.
